UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A FONT OF PRINTING-TYPE.

SPECIFICATION forming part of Design No. 20,547, dated March 3, 1891.

Application filed February 6, 1891. Serial No. 380,507. Term of patent 7 years.

To all whom it may concern.

Be it known that I, HERMAN IHLENBURG, a citizen of the United States, and a resident of Philadelphia, Pennsylvania, have invented a Design for a Font of Type, of which the following is a specification.

My design for a font of type is clearly illustrated in the accompanying typographical impression.

10 The general character of the type is that of a light-faced solid fancy letter; and the font consists of the upper and lower case and the numerals. The cross-lines of the letters A, E, F, H, and R are above the center of the letter. The scroll of the letter J is short, while the inner lines of the letter M are joined at the center of the letter. The tail of the letter Q extends well into the body of the let-

ter, and the letter U is narrower at the top than at the bottom. The corners of the square letters have slight projections, as clearly shown. The letters of the lower-case are in keeping with the letters of the upper-case. The numerals are also in keeping with the letters of the upper-case.

25

I claim—

The design for a font of type, substantially as herein described, and as shown in the accompanying typographical impression.

In testimony whereof I have signed my name to this specification in the presence of 30 two subscribing witnesses.

HERMAN IHLENBURG.
